UNITED STATES PATENT OFFICE

2,448,969

KEY RETAINER

Roy Bentley French, Superior, W. Va.

Application June 18, 1946, Serial No. 677,559

2 Claims. (Cl. 70—456)

1

This invention relates to a key retainer and has for its primary object to support one or more keys in a position for ready use.

Another object is to keep a collection of keys together in a convenient and compact form for introduction into the pocket or purse of the user.

The above and other objects may be attained by employing this invention which embodies among its features a bar upon which keys are adapted to be threaded, a head at one end of the bar, a keeper detachably secured to the end of the bar opposite the head and spring pressed plungers encircling the bar between the head and the keeper for engagement with the opposite sides of one or more keys supported on the bar.

Other features include a spring pressed plunger encircling the bar and telescopically associated with the head, and a like spring pressed plunger encircling the bar and telescopically associated with the keeper, said plungers being adapted to hold one or more keys threaded on the bar at a point substantially midway between the head and the keeper.

In the drawings:

Figure 1 is a side view of a key retainer embodying the features of this invention, showing a group of three keys supported thereon,

Figure 2 is a longitudinal sectional view through Figure 1,

Figure 3 is a side view of the bar and a fragment of the head, showing the re-entrant groove by which the keeper is attached to the bar,

Figure 4 is a side view of the keeper removed from the bar,

Figure 5 is an end view of the keeper, and

Figure 6 is a fragmentary perspective view of two keys, typical of those which are to be supported by the bar.

Referring to the drawings in detail my improved key retainer comprises a bar 10 to one end of which is fixed a tubular head 11, the walls of which overlie a portion of the bar in concentric spaced relation thereto. Formed at the inner end of the head 11 is an inturned flange 12 forming a stop for the key engaging plunger to be more fully hereinafter described.

The inner edge of the flange 12 is spaced concentrically from the bar 10 and slidably mounted on the bar between the flange 12 and the periphery of the bar is a tubular sleeve 13 provided at one end with an outstanding annular flange 14 which is adapted to ride within the tubular head 11, while the opposite end of the sleeve 13 is provided with a similar outturned annular flange 15 forming a presser head for en-

2

gagement against the keys which are retained on the bar. An inturned flange 16 is formed on the end of the sleeve 13 and the opening therethrough is concentric with the bar 10 and has a sliding fit thereon so that the sleeve 13 will be held in spaced concentric relation to the bar 10. A compression coil spring 17 surrounds the bar 10 between the flange 16 and the inner end of the head 11 so as to normally urge the sleeve 13 or plunger outwardly of the head.

Formed adjacent the end of the bar 10 opposite the head 11 is a re-entrant groove 18, and slidably fitted over the grooved end of the bar 10 is a keeper designated generally 19. The keeper 19 comprises a tubular body 20 having a head 21 formed with a central opening 22 into which projects a radial pin 23 for engagement in the groove 18 so as to hold the keeper 19 in proper assembled relation to the bar 10 and head 11. The tubular body 20 of the keeper 19 is provided at the end opposite the head 21 an inturned flange 23 forming an axial opening 24 which aligns axially with the opening 22 and in which is slidable a plunger 25 comprising a tubular body having an outstanding annular flange 26 at one end which rides in the tubular body 20, and formed at the end of the sleeve 25 opposite the out-turned flange 26 is an inturned flange 27 which rides on the bar 10 and serves to hold the sleeve 25 in spaced concentric relation thereto. A presser flange 28 corresponding in all respects to the flange 15 of the plunger 13 extends outwardly from the outer end of the sleeve 25 as will be readily understood upon reference to the drawings. Extending between the inturned flange 27 and the inner face of the end wall 21 is a compression coil spring 29 which corresponds in all respects to the spring 17 previously described, so as to urge the sleeve 25 outwardly of the tubular body 20.

In use assuming that the parts are separated it will be understood that keys 30 are threaded onto the bar as illustrated in Figures 1 and 2 until they are moved into engagement with the flange 15 of the telescopic sleeve 13 mounted in the head 11. After the desired number of keys have been placed on the bar the keeper 19 is mounted thereon by introducing the end of the bar into the opening formed by the inturned flange 27 so that the spring 29 surrounds the bar and the end of the bar 10 will enter the opening 22. By properly aligning the pin 23 with the re-entrant groove 18 it will be evident that the keeper may be locked in place on the end of the bar opposite that carrying the head 11, thus causing the

sleeves 13 and 25 to telescope into their respective end members so as to compress the springs 17 and 29 and cause the flanges 15 and 28 frictionally to engage the opposite side faces of the keys 30. Obviously a key may be swung outwardly away from the group of keys so that the bit thereof extends radially from the axis of the bar 10 ready for use. Should it be desired to remove a key from the bar it is only necessary to press inwardly on the keeper 19 and rotate the bar and keeper relatively so as to move the pin through the re-entrant groove 18 to permit extraction as a keeper from the end of the bar. By thus removing the keeper keys may be added to those already on the bar or certain of the keys mounted thereon may be removed, and upon replacing the keeper it will be evident that the parts will assume their original positions, with the keys independently rotatable about the bar 10.

While in the foregoing there has been shown and described the preferred embodiment of this invention it is to be understood that minor changes in the details of construction, combination and arrangement of parts may be resorted to without departing from the spirit and scope of the invention as claimed.

I claim:

1. A key retainer comprising a bar upon which keys are adapted to be supported, a head at one end of the bar, a keeper detachably secured to the end of the bar opposite the head, a spring pressed plunger encircling the bar and telescopically entering the head and a spring pressed plunger en-

circling the bar and entering the keeper said plungers engaging opposite sides of one or more keys supported on the bar and holding said keys substantially midway between opposite ends of the bar and cooperating flanges on the head, the keeper and the plungers to limit the movements of the plungers toward one another.

2. A key retainer comprising a bar upon which keys are adapted to be supported, a head at one end of the bar, a keeper detachably secured to the end of the bar opposite the head, a spring pressed plunger encircling the bar and telescopically associated with the head and a like spring pressed plunger encircling the bar and telescopically associated with the keeper, said plungers being adapted to hold one or more keys threaded on the bar at a point substantially midway between the head and the keeper.

ROY BENTLEY FRENCH.
